CLAYTON M. BOUDETTE, OF REVERE, MASSACHUSETTS

SOUND PRODUCING DEVICE

Application filed August 30, 1932. Serial No. 631,039.

In radio loud speakers of the electrodynamic type where the voice-current coil is disposed in the air gap between the core and pole-piece of a magnet, usually an electro-
5 magnet, it is desirable to reduce the radial length of such air gap to a minimum and it is essential that said diaphragm and the actuating coil attached thereto be accurately centered with respect to said core so that said coil
10 may have free and unrestricted longitudinal movement, and no transverse motion, in said gap.

This invention involves a novel coil-supporting means which, while permitting free
15 longitudinal movement of the voice current coil in the air gap, accurately centers said coil and prevents any transverse movement thereof, thereby eliminating all danger of contact between said coil and the magnet ele-
20 ments. By means of this improved centering device a much narrower air gap can be used than is possible with the coil-centering means heretofore employed and the diaphragm and
25 voice coil are permanently and accurately centered and aligned with respect to the mag-
netic system.

The preferred form of centering device is a washer of thin flexible non-hydroscopic material such as celluloid, metal, bakelite, non-
30 porous paper and the like which may be pro-
vided with corrugations, either concentric or spiral, or of any other suitable configuration to increase the flexibility thereof longitudinally without unduly reducing the lateral
35 stiffness of the same. The voice-coil support-
ing-cylinder preferably projects through the central aperture of the centering washer and is cemented to the latter and the apex portion of the diaphragm, if the latter be of the coni-
40 cal type, with the result that the washer acts as a diaphragm-supporting means, as well as a means for centering and aligning the voice coil and diaphragm with respect to the mag-
netic structure.

45 In the drawings which accompany and form a part of this specification—

Figure 1 is a plan view of a coil-centering washer embodying the present invention;

50 Fig. 2 is a section taken on the line 2—2 of Fig. 1;

Fig. 3 is a plan view of another form of centering washer;

Fig. 4 is a section taken on the line 4—4 of Fig. 2;

Fig. 5 is a longitudinal central section of 55 a radio loud speaker provided with the coil-
centering diaphragm-supporting washer shown in Fig. 1.

In the particular drawings selected for more fully disclosing the principle of my in- 60 vention and which are to be considered as illustrative merely and not as restrictive, 10 is a washer formed of thin flexible non-porous material, such for example, as celluloid and provided with concentric corrugations 11 be- 65 tween the peripheral portion 12 and the central aperture 13. The corrugated portion of the apertured disc or washer between the support for the peripheral portion thereof and said central aperture must have such radial 70 length as will permit of sufficient longitudinal movement of said disc and the parts thereto attached to effect the faithful reproduction of low notes. In the present instance, as shown in the accompanying drawings which are full 75 size, except that the thickness of the washer is greatly exaggerated for clearness of illustration, the ratio of the diameter of the free or vibrating portion of the disc, i. e., the portion thereof within the inner periphery of 80 said support, to the diameter of said central aperture is $2\frac{1}{2}$ to 1, approximately, and the ratio of the radial length of the corrugated portion of said disc to the thickness of the disc is approximately 250 to 1. I do not, 85 however, limit myself to such ratios, the requirement being that the amplitude of range of vibration of the disc must be relatively large if low notes are to be reproduced with fidelity. By the loud speaker shown in the 90 drawings, the lowest notes of the musical scale are reproduced faithfully because a range of vibration of $\frac{1}{4}$ inch can be obtained without breaking or cracking the disc. It will be understood of course that I do not limit myself to a loud speaker of the exact size shown in the drawings and that the principle underlying the speaker herein specifically disclosed is applicable to speakers larger and smaller than the one illustrated in the drawings.

I am aware that diaphragms with corrugated peripheral portions have been proposed for loud speakers of the horn type, but in such case the radial length of the corrugated portion thereof must be small compared to the diameter of the diaphragm to ensure the lateral stiffness necessary for preventing the rocking of the diaphragm, with the result that the vibration range of such diaphragms 10 is much too small for the faithful reproduction of low notes if said diaphragm were used in a speaker of the cone type.

Inasmuch as the corrugation of a coil-centering disc reduces the lateral stiffness thereof 15 and as such disc must have sufficient lateral stiffness to permit the use of an extremely narrow air gap, it follows that the radial length of the corrugated portion of the disc must necessarily be a compromise between 20 longitudinal flexibility and lateral stiffness. Such radial length must be sufficiently great to impart to the disc such elasticity as will permit, other things being equal, of a relatively large vibration range, and yet not so 25 great as to reduce the lateral stiffness of the disc to the degree that will prevent the use of a narrow air gap with very small clearance between the voice coil and the side of said gap.

30 It will be obvious that if a voice coil of larger diameter than that shown in the drawings is used, the ratio above-mentioned would be smaller than $2\frac{1}{2}$ to 1.

It will be obvious also that the radial length 35 of the corrugated portion of the disc, for a given range of vibration, is dependent, other things being equal, upon the thickness of the disc, and further, that such radial length for a given range of vibration and given thickness 40 of disc is dependent upon the size and weight of the cone. For example, if the thickness of the disc be reduced, the radial length of the corrugated portion thereof also may be diminished, and if the size or weight 45 of the cone be augmented, such radial length may be reduced, and vice versa.

In view of the various factors entering into the determination of the radial length of the corrugated portion of the washer or disc, it is 50 to be understood that I do not limit myself to any particular ratio of diameter of the free portion of the disc to diameter of the central aperture thereof, or to any particular ratio of radial length to thickness of disc, and that 55 I desire to cover by the appended claims a loud speaker of the cone type in which the radial length of the corrugated portion of the centering disc is sufficiently great to permit of the range of vibration required, other

60 things being equal, for the faithful reproduction of low notes without sacrificing the lateral stiffness necessary to permit the use of an extremely narrow air gap. If celluloid is employed for the washer, the corrugations 65 conveniently may be formed by heating the

disc and pressing the corrugations thereinto by a die.

In Fig. 3 the disc is provided with concentric corrugations 14. It will be understood that as the purpose of the corrugations is to 70 increase the flexibility of the washer longitudinally without unduly reducing the lateral stiffness thereof, such corrugations may be of any shape or configuration that will effect the desired result. 75

Referring to Fig. 5, the electromagnet 15 is provided with a core 16 and pole-piece 17, apertured to receive said core. The voice-current coil 18 is wound on the coil-supporting cylinder 19 and is disposed in the air gap 80 between the core and pole-piece. The outer flange 20 of the diaphragm 21, herein shown as a cone, is flexibly supported by the flange 22 of the pan 23 secured to the magnet structure by bolts 24. The lower portion of said pan forms an annular support 25 for the outer peripheral portion of the centering washer which preferably is cemented to said annular support. Preferably a thin coating of cement is placed on the coil-supporting cylinder 90 and the latter is then passed through the apex portion of the cone in order to secure these two elements together. The central aperture of the centering washer may be provided with a flange 26 in order to facilitate the cementing of said washer to the coil-supporting cylinder, which preferably is secured both to the diaphragm and washer. It will be understood of course that this invention is not limited to the particular means disclosed for 95 securing the aforesaid elements together, inasmuch as many alternative means will readily occur to those skilled in the art for accomplishing this purpose. 100

It has been found in practice that the use of 105 a centering washer of the character described herein permits the permanent and accurate centering and aligning of the diaphragm and voice coil with respect to the magnet structure and makes possible a substantial reduction in 110 the radial length of the air gap. The flexibility of the centering washer effected by the corrugations is such that the voice coil has free and unimpeded movement longitudinally with respect to the air gap while lateral stiffness thereof is not reduced sufficiently to 115 permit any transverse movement of said coil in said gap.

It will be obvious that various changes in 120 structure and relationship may be made by those skilled in the art without departing from the scope of the invention as defined by the appended claims.

I claim:

1. A sound-producing device comprising in combination, a cone diaphragm flexibly supported at its base, an actuating coil secured to said diaphragm, a corrugated imperforate coil-centering diaphragm-supporting 125

130

disc of thin flexible material, and a support for the peripheral portion of said disc.

2. A sound-producing device comprising in combination, a cone diaphragm flexibly supported at its base, an actuating coil secured to said diaphragm, a corrugated coil-centering diaphragm-supporting disc of thin flexible material, and a support for the peripheral portion of said disc, the corrugated portion of said disc having sufficient radial length to permit of free longitudinal movement thereof without unduly reducing the lateral stiffness of the same.

3. A sound-producing device comprising in combination, a cone diaphragm flexibly supported at its base, an actuating coil secured to said diaphragm, a coil-centering diaphragm-supporting disc of thin flexible material provided with concentric corrugations, and a support for the peripheral portion of said disc, the corrugated portion of said disc having sufficient radial length to permit of free longitudinal movement thereof without unduly reducing the lateral stiffness of the same.

4. A sound-producing device comprising in combination, a cone diaphragm flexibly supported at its base, an actuating coil secured to said diaphragm, a coil-centering diaphragm-supporting disc of thin flexible material provided with spiral corrugations, and a support for the peripheral portion of said disc, the corrugated portion of said disc having sufficient radial length to permit of free longitudinal movement thereof without unduly reducing the lateral stiffness of the same.

5. In a sound-producing device having a diaphragm flexibly supported at its base and an actuating coil secured thereto, a corrugated imperforate coil-centering diaphragm-supporting disc of thin flexible non-hydroscopic material, and a support for the peripheral portion of said disc, the corrugated portion of said disc having sufficient radial length to permit of free longitudinal movement thereof without unduly reducing the lateral stiffness of the same.

6. In a sound-producing device having a cone diaphragm flexibly supported at its base and an actuating coil secured thereto, a corrugated coil-centering diaphragm-supporting celluloid disc, and a support for the peripheral portion of said disc, the corrugated portion of said disc having sufficient radial length to permit of free longitudinal movement thereof without unduly reducing the lateral stiffness of the same.

7. A sound-producing device comprising in combination, a cone diaphragm flexibly supported at its base, a magnet having a core and a pole-piece, a coil support, an actuating coil carried by said support, said coil being disposed in the air gap between said core and pole-piece and said coil-support being se-

cured to said diaphragm, a thin corrugated disc for centering said coil, said disc being of thin flexible material and having a central aperture for receiving said coil support, and a support for the peripheral portion of said disc, the corrugated portion of said disc having sufficient radial length to permit of free longitudinal movement thereof without unduly reducing the lateral stiffness of the same.

8. A sound-producing device comprising in combination, a cone diaphragm flexibly supported at its base, a coil support, an actuating coil carried by said support, a corrugated coil-centering disc formed of thin flexible material and provided with a central aperture, a support for the outer peripheral portion of said disc, said coil support passing through said aperture and being secured to said diaphragm and to said disc, and a magnet having a core and a pole-piece, said coil being disposed in the air-gap between said core and pole-piece and the corrugated portion of said disc having sufficient radial length to permit of free longitudinal movement thereof without unduly reducing the lateral stiffness of the same.

In testimony whereof I affix my signature.
